IRA E. McCABE, OF CHICAGO, ILLINOIS

CONSTANT CURRENT IGNITION DEVICE

Application filed May 9, 1930. Serial No. 451,187.

This invention relates to improvements in ignition devices for fluid fuel burner mechanisms and more particularly to a constant current ignition device for a hot wire ignition system.

Not only does the commercial voltage fluctuate in the same locality but the commercial voltage varies in different localities. A hot wire ignition system for fluid fuel burners includes an electrical resistance element adapted to be heated to incandescence by the commercial current to ignite the fluid fuel. Constant current transformers have been included in the ignition circuit to insure the passage of a constant current through the resistance element irrespective of the fluctuations or variations in commercial lines.

It is an object of this invention to provide such a constant current ignition system with means whereby should the resistance ignition element by any cause become destroyed or inoperative thereafter upon an initial start fuel cannot be supplied to the burner.

In all hot wire ignition systems for fluid fuel burners it is necessary to first bring the resistance ignition element to incandescence before fuel is supplied. This preliminary heating period is called in the trade "pre-heating". Different types of burners require pre-heating periods of different duration, so that variations in the pre-heating period may cause the mechanism to become inoperative or may cause dangerous results such as delayed ignition. It is a further object to provide means, when once adjusted to the particular burner, to produce a constant pre-heating period irrespective of fluctuations or variations in the commercial current.

With these and other objects in view, reference is made to the accompanying sheets of drawings which illustrate a preferred form of this invention with the understanding that minor detail changes may be made without departing from the scope thereof.

In the drawings:

Figure 1 is a view illustrating a stack switch mechanism in front elevation with a constant current transformer and parts actuated thereby in diagram with a wiring diagram showing the electrical connections to the various parts of a fluid fuel burner system.

Figure 2 is an enlarged detail view of the constant current transformer panel in front elevation with parts actuated thereby shown in central vertical section and the cover in section.

Figure 3 is a view in side elevation of Figure 2 with the cover on one side shown in section.

While it is preferable to employ the stack switch illustrated on the panel 1 any stack switch which upon the establishment of combustion will close the motor circuit before the ignition circuit is broken will suffice. The particular stack switch illustrated in this embodiment of this invention is a commercial article and is fully disclosed in this applicant's prior copending application, Serial No. 418,684, filed January 6, 1930, and includes an ignition switch 2 and a switch 3 in the running motor circuit which are shown in the normal position assumed when the burner mechanism is idle, that is, with the ignition switch 2 closed and the motor running switch 3 open. The normal operation of this stack switch mechanism causes the motor running switch 3 to close before the ignition switch opens after the establishment of combustion.

A constant current transformer is mounted on the panel 4 having a moveable or floating primary coil 5 and a stationary secondary coil 6. At one side of the transformer a solenoid is mounted, the winding 7 of which is preferably of the same size and material as the winding of the secondary coil 6 with one end of the winding 7 connected to the secondary coil 6 and the other to one terminal

of an electrical resistance igniter element 8, the other terminal of which is connected in circuit with the other pole of the secondary coil 6.

5 A starting motor switch 9 is mounted above the solenoid which normally assumes the open position when the solenoid is deenergized. The core 10 of the solenoid preferably mounts at its lower end the piston 11 in the dash 10 pot 12 secured upon the under side of the solenoid which is adjustable to limit the time of movement of the core 10 in arriving at the upward end of its movement when the solenoid is energized. The upward movement 15 of the core 10 acts, preferably through shaft 13, to close the starting motor switch 9 and maintain it in closed position as long as the solenoid remains energized.

The manner in which the destruction of the 20 ignition element will thereafter prevent the initial supply of fuel and the manner in which the pre-heating period is maintained constant will be more readily understood by following the circuits shown on the wiring diagram 25 on Figure 1. As previously stated, when the burner mechanism is idle the ignition switch 2 is normally in closed position and the starting motor switch 9 and running motor switch 3 are normally in the open position, as shown 30 on Figure 1. The incoming commercial current travels through wire 14 passing through the room thermostat T and boiler control B to the binding post 15 and from there to the binding post 16 and from thence through the 35 holding magnet H to the normally closed safety switch S, and then to binding post 17 and from binding post 17 through the normally closed ignition switch 2 to binding post 18 and from there through binding post 40 19 to the winding of the primary coil 5. The other end of the winding conveys the current through wire 20 through binding post 21 back to the commercial line.

The energizing of the primary coil 5 induces a current of constant intensity in the winding of the secondary coil 6, so that this constant current is conveyed from one end of the winding of the secondary coil 6 through wire 22 to one end of the winding 7 of the 50 solenoid and from thence through wire 23 through the resistance ignition element 8 back to the other end of the winding of the secondary coil 6. The energizing of the solenoid by the passage of this constant current 55 through its winding 7 imparts an upward movement to the core 10 which after a pre-determined time will close the starting motor switch 9. The piston 11 carried by the core 10 having been once adjusted so that its passage upward in the dash pot 10 to close the starting motor switch is that required for the pre-heating period of the ignition element 8 for the particular burner mechanism will maintain the pre-heating period constant during each initial operation of the control sys-

tem, because the constant current from the secondary coil 6 will always pass with the same constant intensity through the windings of the solenoid, irrespective of the fluctuations or variations of the commercial 70 voltage.

The closing of the starting motor circuit causes the incoming current which passes through the closed safety switch S to the binding post 17 to branch so that part of it 75 passes therefrom through wire 24 to binding post 25 and from thence through the closed starting motor switch 9 to binding post 26 and from thence to binding post 27 and from there to binding post 28, passing through the 80 release mechanism of the safety switch to binding post 29 and from there to the binding post 30 and from this binding post to the burner mechanism motor M, and from the other pole of the motor to binding post 21 85 where it returns by the return wire 20 to the commercial line. It is, therefore seen that the closing of the room thermostat T, which instrument is of commercial manufacture and is customarily a part of the control system of a fluid fuel burner mechanism, which remarks apply as well to the boiler control B, the constant current transformer is energized and a pre-determined time thereafter the starting motor switch is closed. 90 The pre-heating period occurs between the initial closure of the thermostat and the closing of the starting motor switch 9. The closing of the motor starting switch starts the motor which supplies fluid fuel to the 100 burner mechanism after the ignition element 8 has been heated to incandescency. Combustion then normally takes place. It is readily seen that should the resistance ignition element 8 be inoperative or be destroyed 105 for any cause, the secondary circuit through the secondary coil 6 of the transformer will not be completed and therefore the windings 7 of the solenoid will not be energized and the starting motor switch will therefore remain in its normal open position so that the burner mechanism motor M cannot be started until the ignition element has been replaced or repaired.

As above stated, the starting of the burner mechanism motor normally initiates combustion. The stack switch mechanism responds to the establishment of combustion and as described in this applicant's said prior application, the running motor circuit switch 3 is 110 closed and thereafter the ignition switch 2 is opened. The closing of the running motor switch 3 closes a circuit so that the incoming current passing through safety switch S to the binding post 17 passes by way of wire 31 through the closed running motor switch 3 to binding post 29 and from thence through wire 24 to binding post 30 to the burner mechanism motor M. This is called the running 120 circuit because as long as combustion con-

125 130

tinues the running motor switch 3 will remain closed. After this running circuit is closed the ignition switch 2 is opened so that the incoming circuit passing through the 5 safety switch S to the binding post 17 is opened through the ignition switch 2 which results in the deenergization of the primary coil 5 of the constant current transformer, whereupon the secondary coil 6 is also de- 10 energized and thereafter the solenoid 7 is likewise deenergized and as the core 10 de-scends the starting motor switch 9 assumes its normal open position.

The normal operation of the room 15 thermostat will eventually open the running circuit of the motor, and after the discontinuance of combustion, the stack switch will return to its normal idle position in which the ignition switch 2 will assume its closed position while the running motor switch 3 will assume its open position and the system will be ready to again initiate combustion when the room thermostat is closed.

It is readily seen that this construction not 20 only prevents initial starting of the burner mechanism motor in case the ignition element is inoperative but also provides in the normal operation a constant pre-heating period of the ignition device, irrespective of the 25 fluctuations or variations in the commercial current.

Should for any reason, while the burner mechanism is operating normally after the room thermostat has closed, the flame fail 30 then the stack switch responsive to combustion returns the running motor switch 3 to open position thereby breaking the circuit through the holding magnet H. As described in said prior co-pending application, 35 the de-energizing of the holding magnet H will release the ignition switch 2, allowing it to return to the closed position. If the room thermostat is closed, the normal starting operation will be repeated but if no flame occurs, the stack switch responsive to combustion 40 remains immobile so that the running motor switch 3 remains in open position, therefore the circuit closed through the starting motor switch 9 passes through the binding post 28, and through the release mechanism of the safety switch to binding post 29, whereby after a predetermined time the safety switch S is released and breaks the motor circuit, causing a complete shut-down 45 and requiring a manual reset before operation can be resumed.

What I claim is:

1. In an electrically controlled fluid fuel burner mechanism, a hot wire ignition system including an electrical resistance igniting element, a constant current transformer, means for energizing the primary coil of the transformer, means connecting the igniting element in circuit with the secondary coil, 60 an electro-magnetic means interposed in the

secondary circuit, and means actuated by the energization of the solenoid to supply fluid fuel to the igniting element, whereby a break in the secondary circuit prevents the supply of fuel to the burner. 70

2. In an electrically controlled fluid fuel burner mechanism, a hot wire ignition system including an electrical resistance igniting element, a constant current transformer, means for energizing the primary coil of the transformer, means connecting the igniting element in circuit with the secondary coil, an electro-magnetic means interposed in the secondary circuit, and means actuated thereby a constant predetermined time after each 75 energization of the primary coil to supply fluid fuel to the igniting device, thereby insuring a constant pre-heating period of the igniting device. 80

3. A constant current ignition device for an electrically controlled fluid fuel burner mechanism including a constant current transformer, means for closing and opening the circuit to the primary coil thereof, an electrical resistance igniting element and a solenoid interposed in the secondary circuit of the transformer, means for opening and closing the circuit to the fuel supply means actuated by the solenoid to close said circuit to supply fuel to the igniting element a predetermined time after each energizing of the 90 secondary circuit of the transformer. 95

4. A constant current ignition device for a hot wire ignition system of an electrically controlled fluid fuel burner mechanism including a constant current transformer and a switch in the control system adapted to connect the primary coil of the transformer to the source of electricity, an electrical resistance igniting element and a solenoid interposed in the secondary circuit of the transformer, and a normally open switch actuated by the energization of the solenoid to close a circuit between the source of electricity and fuel supply means to supply a predetermined time after each energizing of the secondary circuit, fluid fuel to the incandescent igniting element, thereby insuring a constant pre-heating of the igniting element previous to the initial supply of fuel. 100

5. A constant current ignition device for a hot wire ignition system of an electrically controlled fluid fuel burner mechanism including in the control thereof a switch mechanism responsive to the establishment of combustion, a constant current transformer, an electrical resistance igniting element and a solenoid in the secondary circuit thereof, an electrically operated means for supplying fuel to the igniting element, a switch in said switch mechanism normally closed to connect the primary coil of the transformer to the source of electricity, a switch normally open and actuated by the 110 115 120 125 130

solenoid to close a circuit from said first switch to initiate the supply of fuel to the igniting element and a switch in said switch mechanism normally open in a circuit from the source of electricity to the fuel supply means, said switch mechanism upon establishment of combustion first closing the switch to maintain the circuit from the source to the fuel supply means and then opening the switch in the transformer circuit, whereby upon each closing of the circuit to the control the supply of fuel is initiated after a constant pre-heating of the ignition element and thereafter the fuel supply is maintained after the transformer is deenergized.
